WRAPPING MACHINE

Robert F. McVicker, Bertil Johnson, Omar Hansen, Jr., and James C. Travis, all of Anderson, Ind., assignors to Lynch Corporation, Anderson, Ind., a corporation of Indiana

Filed May 15, 1961, Ser. No. 110,144
18 Claims. (Cl. 53—66)

This invention relates to a wrapping machine of the general type shown in the Sandberg patents, No. 2,283,096 and No. 2,283,097 which combines, all in one unitary structure, mechanism for forming "boats" for supporting product such as candy bars, cookies and the like, or forming merely "cards" to facilitate the packaging of the product by applying one or more wrappers thereto.

One object of the invention is to provide a wrapping machine having a side-by-side arrangement of rolls of wrapping paper and a roll of cardboard from which wrappers, and cards or boats respectively are formed, together with an arrangement for conveying the cards or boats after they are cut from the roll of cardboard into position for receiving thereon the product to be wrapped whereupon the cards or boats and product are transferred to a position for wrapping, subsequently wrapped and discharged from the machine.

Another object of our invention is to provide card feeding and cutting mechanism having an expandable arbor for a roll of cardboard strip and provided with friction means to restrain the roll of cardboard against free rotation, the arbor having a spider against which the roll of cardboard is positioned and which is adjustable for different widths of cardboard strip, cutoff mechanism being provided to cut the strip into cards, together with bead-forming means for the sides of the cards and a means to rapidly project the cutoff card into a transfer conveyor.

Still another object is to provide scoring rolls and boat forming mechanism for the cardboard strip and cards, selectively useable or not as required, the scoring rolls and the boat forming mechanism being adjustable as to width.

A further object is to provide a card transfer conveyor for turning the cards or boats 180°, thus providing two feeding stations, if desired on opposite sides of the machine and contributing to compactness of the machine yet enabling it to perform at a high production rate, means being provided after the second feed station to push the cards or boats and product from the transfer conveyor to a position beneath a wrapper for subsequently wrapping the product and card or boat within the wrapper.

A further object is to provide wrapper feeding and cutting mechanism utilizing a light beam responsive to patterns on the wrapping material to assure cutting the wrappers at the proper dividing line between them, the light beam mechanism being adjustable for either direct or reflected light and the wrapper feeding mechanism being adjustable as to both width and length of wrapper.

Still a further object is to provide a folding way which is adjustable as to width and length so that a great variety of product sizes may be accommodated in our wrapping machine.

An additional object is to provide wrapper tucking mechanism in the form of tucker blades which are readily interchangeable with others of different width, and to mount the tucker blades for reciprocation under the product and wrapper for tucking end flaps and one side flap of the wrapper under the package, adjustable throw lever mechanisms being provided for the tucker blades to accommodate different size packages throughout a considerable range of sizes.

Another additional object is to provide a take-away

2

conveyor including heat sealing mechanism and hold-down belts which are adjustable as to width to accommodate various sizes of packaged product, and also adjustable vertically for different thicknesses thereof, a separate motor being provided for actuating a take-away conveyor and its hold-down belts.

With these and other objects in view, our invention consists in the construction, arrangement and combination of the various parts of our wrapping machine, whereby the objects above contemplated are attained, as hereininafter more fully set forth, pointed out in our claims and illustrated in detail on the accompanying drawings, wherein:

FIG. 1 is a diagrammatic perspective view showing a roll of cardboard, rolls of wrapping paper, product and completed packages in sequence as they pass through our machine to illustrate in general the various operations thereof.

FIG. 2 is an enlarged perspective view from below showing a completed package as discharged from our wrapping machine.

FIG. 3 is a rear elevation (intake end) of our wrapping machine.

FIG. 4 is a plan view thereof.

FIG. 5 is a right side elevation thereof (as viewed from the right side of FIG. 3).

FIG. 6 is a vertical sectional view on the line 6—6 of FIG. 5 to show the supporting means for a roll of cardboard.

FIG. 7 is a diagrammatic view to show the mechanical operative connections between a drive motor and various instrumentalities of our wrapping machine.

FIG. 8 is an enlarged plan view of a folding way and adjacent parts of our wrapping machine in accordance with the indicating line 8 shown adjacent the lower part of FIG. 4.

FIG. 9 is an enlarged rear elevation to the portion indicated by the bracket 9 adjacent the top of FIG. 3 and looking in the direction of the arrow 9 adjacent the bottom of FIG. 8.

FIG. 10 is a further enlarged sectional view on the line 10—10 of FIG. 9 to show an adjustable leverage feature.

FIG. 11 is an enlarged view on the line 11—11 of FIG. 3 and turned 90° showing a plan view of part of the drive mechanism for our wrapping machine.

FIG. 12 is a vertical sectional view taken on the line 12—12 of FIG. 11.

FIG. 13 is a further enlarged vertical sectional view on the line 13—13 of FIG. 8 through a folding way and associated instrumentalities.

FIG. 14 is a vertical sectional view on the line 14—14 of FIG. 13.

FIG. 15 is an enlarged vertical sectional view on the line 15—15 of FIG. 3 showing an electric eye mechanism for controlling wrapper feed adjustment.

FIG. 16 is a plan view of FIG. 15.

FIG. 17 is an elevation of a portion of FIG. 15 as indicated by the line 17—17 and showing the electric eye adjusted for transmitted light.

FIG. 18 is a similar view showing the electric eye adjusted for reflected light.

FIG. 19 is an enlarged plan view, indicated by the line 19 of FIG. 4, of mechanism for cutting a roll of cardboard into cards and forming them into "boats," the mechanism being rotated 180° with respect to FIG. 4.

FIG. 19a is a vertical sectional view on the line 19a—19a of FIG. 19.

FIG. 19A is a plan view similar to FIG. 19 showing a substitute mechanism for cutting the roll of cardboard into cards without forming boats.

FIG. 20 is a vertical sectional view on the line 20—20 of FIG. 19.

FIG. 20^a is a fragmentary detail view of that portion of FIG. 20 within the area 20^a.

FIG. 20A is a similar vertical sectional view on the line 20A—20A of FIG. 19A.

FIG. 21 is a vertical sectional view on the line 21—21 of FIG. 20 to show gearing connections between card-board scoring rolls.

FIG. 21A is a vertical sectional view on the line 21A—21A of FIG. 20A showing card edge crimping rolls.

FIG. 22 is a perspective view of a boat former shown in FIGS. 19 and 20.

FIG. 23 is an enlarged plan view of approximately the left one-third of FIG. 4 showing a card and boat transfer conveyor.

FIG. 24 is an enlarged elevation of a portion of FIG. 23 indicated by the line 24—24.

FIG. 25 is a vertical sectional view on the line 25—25 of FIG. 23.

FIG. 26 is a vertical sectional view on the line 26—26 of FIG. 25.

FIG. 27 is a perspective view of a product pop-up switch and associated parts.

FIG. 28 is a perspective view of a no-product switch and associated parts.

FIG. 29 is an enlarged plan view of paper cutoff mechanism, being the part of FIG. 4 indicated by the line 29 and turned 180°.

FIG. 30 is an enlarged vertical sectional view on the line 30—30 of FIG. 29 illustrating wrapper hold-down rollers.

FIG. 31 is an end elevation of FIG. 29 from the left side of the figure as indicated by the arrow 31.

FIG. 32 is an enlarged vertical sectional view on the line 32—32 of FIG. 31 showing wrapper cutoff mechanism and associated parts.

FIG. 33 is an enlargement of the lower left portion of FIG. 12 with parts broken away and other parts shown in section to illustrate particularly an elevator operating mechanism and a mechanism housing therefor.

FIG. 34 is a side elevation of that portion of FIG. 33 indicated by the bracket 34.

FIG. 35 is a vertical sectional view on the line 35—35 of FIG. 33 to illustrate details of the mechanism within the housing.

FIG. 36 is a further enlarged side elevation of pusher operating mechanism shown in the upper left quarter of FIG. 12.

FIG. 37 is an end elevation of FIG. 36 in accordance with the arrow 37 adjacent the right side thereof.

FIG. 38 is an enlarged elevation of a take-away conveyor in accordance with the indicating line 38—38 of FIG. 4.

FIG. 39 is a plan view of FIG. 38.

FIG. 40 is an enlarged vertical sectional view on the line 40—40 of FIG. 39 showing the cooperation of hold-down belts and heaters for packaged articles; and

FIG. 41 is an enlarged vertical sectional view on the line 41—41 of FIG. 38 showing adjusting instrumentalities for the take-away conveyor of our wrapping machine.

General Operation of Our Wrapping Machine

On the accompanying drawings and referring first to FIG. 1, we have used the reference numeral 10 to indicate a roll of cardboard and 12 a strip thereof as fed from the roll into our wrapping machine. In the wrapping machine the strip 12 is cut into individual cards 14 which may also be formed with sides 16 to form "boats" if desired. The cards 14 (or boats 14—16) are transferred by a conveyor as indicated by arrows 15 to turn 180° in the machine and then travel in a straight line as indicated by an arrow 19 to a position or designated station D. During their travel, product 17 such as candy bars, buns, sandwiches, cookies or the like are manually or automatically deposited thereon, and the cards or boats and product finally reach another station or position indicated at A, being pushed from D to A as indicated by 70

the arrow 21. Two feed stations (F¹) and (F²) are shown with alternate boats receiving product at each, or all boats may receive product at only one feed station.

A roll of wrapping paper 13 is provided from which a strip 20 thereof is fed, and cut into individual wrappers 22 which finally reach a position indicated at B directly above position A. We also provide a roll of overwrap 24 from which a strip 26 thereof extends to be cut into individual wrappers 28 which also are successively delivered simultaneously with the wrappers 22 to the position B. The sheets 22 may be of waxed paper for instance while the overwrap sheets 28 may be of tinfoil or the like. In some instances the sheets 22 may be eliminated if only a single wrapper is desired for the product 17.

The cards 14 (or boats 14—16) at position A are elevated (arrow 23) against the wrappers 22—28 and through a folding way (indicated by bracket F in FIG. 1 and hereinafter described in detail) which results in side flaps 30 and end flaps 32 being bent downwardly over the product and card or boat, whereupon first and second bottom flap folders operate in the directions of the arrows 34 and 36 to fold the end flaps 32 under the resulting package P as shown in FIG. 2. Thereupon a third bottom flap folder operates in the direction of the arrow 38 for folding the third flap 30 under the package, and the package is then pushed in the direction of the arrow 49 which results in the fourth bottom flap 30 being folded under the package again as shown in FIG. 2 wherein reference is also made in parentheses to the arrows 34, 36, 38 and 40 in relation to the bottom flap folding operation and the four bottom flaps are labeled. Having described in general the packaging operations which take place in our machine we will now describe the machine in detail.

Card Feeding and Cutting, and Boat Forming Mechanism

Referring to FIGS. 3, 4 and 5 the frame of our wrapping machine is supported on four posts 42, 44, 46 and 48. Projecting from the right side of the machine in FIG. 3 (see also FIGS. 4 and 5) is a vertical plate 50 which supports a shaft 52 for the roll of cardboard 10 (omitted from FIG. 5). A sleeve 54 is rotatable on the shaft 52 and carries a spider 56 having a split hub 58. A clamp lever 60 coacts with the hub to fix the spider on the sleeve. An arbor for supporting the roll 10 of the cardboard is formed of three beveled edge washers 62 carrying two garter springs 64 for expansion in the open center of the roll to retain it against the spider 56, and a nut 66 adjusts the expansion of the springs. The clamp lever 60 may be loosened to adjust the spider 56 axially of the sleeve 54 for different widths of cardboard, which is centered on the arbor 62—64 and the lever 60 manipulated to clamp the hub 58 to the sleeve. The arbor 62 is provided with friction means to restrain its free rotation. This means comprises a brake drum 67 on the sleeve 54 with which a brake band 68 (see FIG. 6) coacts, a spring 69 being provided to keep the band at a predetermined tension. This tension may be varied by adjusting a nut 70. A stud 71 projects from the plate 50 and carries a pair of spaced washers 65 to keep the band on the drum.

The cardboard strip 12 from the roll 10 is fed over an idler roller 72 shown at the left end of FIGS. 19 and 20 and between side guide plates 74 which are adjustable as to the spacing between them by means of an adjusting screw 76 having right and left hand threads and terminating in a hand wheel 78 to effect the desired adjustment. The side guide plates 74 may accordingly be adjusted for width of cardboard strip 12. The parts just enumerated are supported on a pair of side frames 137 which in turn are secured to a channel-shaped frame member 152. Each plate 74 has a hole 75 therein slightly larger than, and receiving the roller 72. The strip of cardboard 12 is pulled over the idler roller 72 and under a roller

73 by a supporting roller 80 and a feed roller 82 geared together by gears 84 and 86 respectively which in turn are driven from a drive gear 88 on a feed drive shaft 90. The roller 73 is for the purpose of removing curl from the cardboard which of course is curled because of coming off the roll 10, and is mounted on an arm 77 secured to a side frame 137 by a clamp screw 79. The arm may be swung to any required position for the roller to remove curl and locked in that position by tightening the clamp screw. In FIG. 20 it is shown for substantially minimum curl-removing action whereas a lower position of the roller 73 would increase such action. This is especially desirable as the inner end of the roll of cardboard is approached, and the adjustment may be changed from time to time, as required during the life of the roll.

Other gears 92 and 94 drive a pair of scoring rolls 96 and a pair of hold-down rollers 98 from the gear 88 and drive shaft 90. Only one roller of each pair is shown in FIG. 21 wherein limiting rollers 97 are also shown which are located on the center line of cardboard 12 as shown in FIG. 19. A pulley 100 on the drive shaft 90 is adapted to be driven from a belt 102 as shown diagrammatically in FIG. 7. The belt in turn is driven from a variable speed drive 104, the input shaft of which is driven by a chain 106 from a shaft 108 that rotates once each cycle of operation of the wrapping machine. The shaft 108 is the output from a gear box 110, the input shaft of which is indicated at 112 and driven by a chain 114 from a main drive shaft 116. The main drive shaft in turn is driven by a drive motor and variable speed reducer shown generally at 118.

Returning to FIGS. 19, 20 and 21, each scoring roll 96 has a scoring disc 95 thereon coating with a scoring groove 99 in its companion hold-down roller 98. The discs 95 and the grooves 99 are adjusted as to distance between them by means of a right and left hand screw shaft 120 on which a hand wheel 122 is provided for effecting the desired adjustment. The scoring rolls 96 have discs 121 for this purpose entering grooves in nuts 123 threaded on the shaft 120. These discs also enter grooves of the rollers 98 so that both rolls 96 and both rollers 98 are simultaneously adjusted.

The supporting roller 80 and the feed roller 82 constitute a measuring means which is variable by adjustment of the variable speed drive 104 as will hereinafter appear. The rollers 80 and 82 feed the cardboard strip 12 to a stationary cutoff knife 124 shown in FIG. 20 and a rotary cutoff knife 126. The knife 124 is mounted on an adjustable rock shaft 125 which can be rocked to compensate for wear and resharpening of the knives 124 and 126. The individual cards 14 are then picked up by a card belt 128 which passes them under eight card hold-down rolls 130. The rolls 130 are arranged in pairs as shown in FIG. 20 and each pair is spring-biased as illustrated at 132 on pins 133. All the rolls are carried by a central arm 134 pivoted on a rod 135 carried by side frames 137 of the wrapping machine. The pivot 135 permits the entire assembly of parts 130, 133 and 134 to be swung upwardly as to the dot-and-dash line position shown at the top of FIG. 20 to clear away any jammed cardboard, product, wrappers and the like.

Adjacent the sides of the cards 14 and spaced on opposite sides of the rolls 130 are rod-like plows 140 for bending the cards at the lines scored by the scoring discs 95 and elevating side flanges 16 thereof from a supine position to beyond an upright position, as illustrated in FIG. 19^a. The rods 140 are bent as illustrated in FIGS. 19, 19^a, 20 and 22, and their forward terminal ends are welded to nuts 142 threaded on a right and left hand adjusting screw 146 coacts with the caps 144 for adjusting the distance between the plows 140. A hand wheel 143 is provided for rotating the adjusting screw 146 as desired. The nuts 142 have perforated arms 144 which slide on a rod 145. This arrangement serves to slidably

guide the plows 140 for varying the spacing between them.

Cooperating with the plows 140 are hold-down blades 141 (see FIG. 19^a) carried by nuts 143 on another right and left hand adjusting screw 136 terminating in a hand wheel 138. The nuts 143 likewise have perforated arms 147 which slide on a rod 149 for guide purposes. The lower edges of the blades 141 have hold-down flanges or plates 150 which contact the top of the card 14 adjacent the plows 140 to insure proper bend-up of the boat flanges 16. The scoring discs 95 can thus be adjusted for distance between scoring marks applied thereto, the plows 140 may be adjusted for proper operation on the particular width of card 14 and its flanges 16, and the two hold-down blades 141 and their plates 150 may be adjusted to the most advantageous distance to cooperate with the plows 140 as thus adjusted in bending the flanges on the card. Likewise the plows 140 may be adjusted to accommodate the particular distance between the lines scored thereon.

For driving the rotary cutoff knife 126 of FIGS. 19 and 20, its shaft 164 is provided with a sprocket 166 driven by the chain 106 as shown in FIG. 7. The card belt 128 is geared thereto by gears 168 and 170. Thus the card belt 128 delivers cards at a constant rate but the strip of cardboard 12 is delivered at a rate variable with respect thereto so as to adjust the length of the cards being cut by the cutoff knife 126. The shaft 164 is provided with spaced flanges 165 to contact the cardboard strip 12 and keep it closely adjacent the stationary knife 124 between the cycles of engagement of the rotating knife 126 with the strip.

When it is desirable to permit free insertion of cardboard or to stop the feed of cardboard 12, plates 174 adjacent the side frames 137 and pivoted thereto at 171 (see FIGS. 19 and 21) may be elevated by rotating a shaft 172 on which the supporting roller 80 rotates. This shaft has flats 173 thereon (see FIG. 20^a) against which the lower edges of the plates 174 normally rest, but by rotating the shaft (it has a handle 175 for this purpose) the plates are swung about the pivots 171 against the bias of springs 176 that normally bias the rollers 82 and 97 into engagement with the cardboard. The tension of the springs is adjustable, the springs being mounted on adjusting screws 178 for this purpose. Thus when the handle 175 is rotated 90° from the position shown in FIG. 20^a, the plates 174 assume the dotted position shown and both the feed roller 82 and the hold-down roller 97 are lifted to either permit free-feeding or stop feeding of the cardboard strip 12 to the cutoff knives 124 and 126, and prevent contact of the cardboard with the rotating scoring discs 95.

At the discharge end of the card belt 128 as shown in FIG. 20 a rapidly rotating roller 158 is provided opposite the last hold-down roll 130 for controlling the discharge of the card 14 onto the transfer conveyor, the chain of which is shown at 160. The roller 158 is mounted on a shaft 159 connected by a coupling 157 to a motor 155 (see FIG. 19A). Thus as soon as the roller 158 grips the forward edge of the card or boat it quickly withdraws it from under the last hold-down roller 130 at the right hand end of FIG. 20 and projects it onto the chain 160 which has spaced, upwardly extending card moving pins 161. Thus the boat is projected against one of the card moving pins of the chain and ahead of the next pin (which is the one that thereafter engages the card or boat to move it along the transfer conveyor).

Card Feeding and Cutting Mechanism

The card feeding and cutting, and boat forming mechanism above described in connection with FIGS. 19, 19^a, 20, 20^a, 21 and 22 may be replaced with a card feeding and cutting mechanism that does not form boats, and this mechanism is shown in FIGS. 19A, 20A and 21A. The mechanism now being described is likewise supported

on side frames 137^a, similar to the side frames 137 but somewhat shorter. Other elements of the previously described mechanism are also similar or identical, and wherever they occur the parts bear the same reference numerals with the addition of *a*.

The cardboard strip 12 from the roll 10 is fed over the idler 72^a shown at the left end of FIGS. 19A and 20A and between the side guide plates 74^a. These side guide plates may likewise be adjusted for width of cardboard strip 12 when the strip is not formed into boats. The strip of cardboard is pulled over the idler roller 72^a and under the roller 73^a by the supporting roller 80^a and the feed roller 82^a driven by the same gearing arrangement described in connection with FIG. 20.

Instead of a scoring roll 96, a bead-forming roll 96^a is provided as shown in FIG. 21A cooperating with a second bead-forming roll 98^a to crimp the edge of the card 14 as indicated at 16^a, thus stiffening and reinforcing it lengthwise thereof. After a card 14 is cut off from the cardboard 12 by the knives 124^a and 126^a, it is picked up by a somewhat shorter card belt 128^a which passes it under only four card hold-down rolls 130^a and is fed to the roller 138^a opposite the last hold-down roll 130^a and discharged onto the transfer conveyor chain 160 to be engaged by a card moving pin 161 thereof, as previously described in connection with a boat. Thus the card is supplied to the transfer conveyor in the same manner as a boat is supplied thereto.

Card Transfer Conveyor

The transfer conveyor above referred to is shown in plan view in FIG. 23, and details thereof are shown in FIGS. 24, 25 and 26. It comprises a bracket 180 secured to the frame of the machine and projecting from the left side thereof as viewed in FIGS. 3 and 4 which supports a spider comprising a main arm 182 and three secondary arms 184. The spider supports portions of a U-shaped chain guide strip 185 for the chain 160 on the outer ends of the three arms 184.

Two supporting arms 186 extend from the bracket 180 toward a feed station designated (F¹) see FIGS. 4 and 23 for supporting card fences 188 and other portions of the guide strip 185. The arms 190 extend in the opposite direction toward a feed station (F²) for supporting card fences 192 and still other portions of the guide strip 185. These fences are on opposite sides of the transfer conveyor chain 160 and two straight stretches of the chain curves through an arc of 180° at the left side of FIGS. 4 and 23 as illustrated. The secondary arms 184 support curved card fences 194 that extend from the left hand ends of the fences 188 to the left hand ends of the fences 192 thus guiding the cards 14 from one straight-away section of the transfer conveyor to the other. The chain 160 is driven by a drive sprocket 196, and extends around idler sprockets 198, 200, 204, 206 and 208 to the terminal ends of the chain guide strip 185 as shown in FIG. 23, the sprocket 198 being adjustable for chain wear take-up. The drive sprocket 196 is driven by a bevel gear drive 210 terminating in a pulley 212 driven by a belt 214 from a pulley 216 as shown in FIG. 7.

Adjustment is provided for various widths of cards 14 by supporting the card fences 188 and 192 on slotted arms 218 secured by means of clamp screws and wing nuts 220 to platforms 222 and 224 adjacent the feed stations (F¹) and (F²). The platforms 222 are supported on the arms 186 whereas the platforms 224 are supported on the arms 190. As for the curved card fences 194 a series of different assemblies having different widths may be provided and quickly interchanged by manipulating lever locks 226. Various sizes of cards also require adjustment of the spider 182-184 in a direction to the right or left in FIG. 23 and this is accomplished by means of an adjusting screw 228 threaded in a boss 230 of the bracket 180. The screw 228 has an unthreaded

part 232 journaled in bearings 234 of the main arm 182 of the spider and geared by bevel gears 236 and 238 to a hand wheel 240 that can be manipulated for adjustment purposes. As for the belt 214 it will be noted that the drive pulley 216 therefor is relatively wide (FIGS. 7 and 37) so that the belt can shift along its width as the adjustment just described requires.

Our transfer conveyor arrangement permits side-by-side location of the roll 10 of cardboard and the rolls 18 and 24 of wrapping material as shown in FIG. 1 in a compact machine that cuts off the cards 14 to one side of the position B and permits product feeding at feed station (F¹) to every other card 14 by one person, and feeding at station (F²) by another person to the remaining empty cards 14. The person at station (F¹) can also watch the packages P as they come from the machine to notice and take care of any malfunctioning whereas the person at station (F²) can watch the wrapping operation at position B and take care of any malfunctioning of the product and wrappers as they pass through the folding way indicated by the bracket 39.

Product and Wrapper Transfer Mechanism

After all the cards 14 have been loaded with product 17 they eventually arrive at the position D in FIG. 1 and must then be transferred (arrow 21) to position A. To accomplish this operation the transfer mechanism shown in FIGS. 11, 12, 36 and 37 is utilized. It comprises a pusher 244 carried by a yoke 246 which is supported by a first parallelogram link arrangement in which the links are indicated 248 and 250, and a second parallelogram link arrangement in which the links are indicated 252 and 254. The upper ends of the links 252 and 254 are connected together by a link 256 whereas the lower end of the link 254 is pivoted to a cam housing 258 and the lower end of the link 252 is secured to a rock shaft 260 journaled in the housing 258. The left hand end of the link 250 as shown in FIG. 36 is pivoted to a bell crank 262 which is connected by a connecting rod 264 to a rock lever 266 secured to a rock shaft 268 journaled in the cam housing 258.

Within the cam housing 258 we provide a pair of cams 270 and 272 having suitably shaped cam grooves in which cam rollers 274 and 276 are positioned. The cam rollers are carried by cam levers 278 and 280 respectively which are secured to the rock shafts 260 and 268 respectively. The cams 270 and 272 are located on a cam shaft 282 having a sprocket 284 thereon driven by the chain 114 as shown in FIG. 7. The pulley 216 for the transfer conveyor chain 160 is also mounted on the cam shaft 282.

The cam 270 oscillates the linkage 252-254 while the cam 272 oscillates the linkage 248-250 with respect to the linkage 252-254. Accordingly a point such as indicated at 235 in FIG. 36 on the pusher 244 will describe a path indicated by the dot and dash line 288 to push the card 14 and product 17 from position D across a platform 245 to position A, then depress and return, then elevate behind the next successive card and product for pushing it from position D to position A. In position A the card and product are under the wrappers 22-28 and ready for elevation against the wrapper and through the folding way F of FIG. 1 as will be described later.

Folding Way Mechanism

Referring particularly to FIGS. 11, 12, 33, 34 and 35, the mechanism for elevating the product and wrapper through the folding way (bracket F of FIG. 13) is illustrated. Within a transmission housing 290 (see FIG. 33) a pair of vertical guide rods 292 are rigidly mounted for guiding a bracket 294. A pair of elevator rods 296 extend upwardly from the bracket 294 through slide bearings 298, and a cross head 300 is mounted on the upper end thereof. Extending upwardly from the cross

head 300 is a pair of elevator posts 302 which may be adjusted toward or away from each other by means of clamp screws 304 passing through slots 306 of the cross head 300 and threaded into the lower ends of the elevator posts.

For reciprocating the bracket 294 on the guide rods 292 between the lower position shown in FIG. 33 and an upper position, a link 308 is pivoted thereto and to the outer end of a cam lever 310 which is pivoted at 312. A cam roller 314 is carried by the cam lever 310 and as shown in FIG. 35 cooperates with a suitable cam groove of an elevator cam 316 mounted on a cam shaft 318. The elevator posts 302 are adapted to elevate the card 14 and product 17 from position A to position C in FIG. 1 as will hereinafter appear through the folding way F.

Wrapper Feeding and Cutting Mechanism

Referring to FIGS. 3, 5, 13 and 29 to 32 inclusive, the roll 18 of wrapping paper and the roll 24 of overwrap material are mounted on arbors 320 and 322 respectively, and retained thereon by a pair of three-arm spiders 324 and 326 as shown in FIG. 3. The strips of wrapping material 20 and 26 extend from the rolls 18 and 24 around suitable rollers and brake type release mechanisms (not described in detail but such as shown in the Sandberg patents hereinbefore referred to), and come together at a roller 328 at the upper right corner of the machine as illustrated in FIG. 3, then toward the position B shown in FIG. 1 which position will also be found in FIG. 13.

The two layers of wrapping material 20 and 26 then pass an electric eye unit E adjacent the roller 328 which unit is shown in detail in FIGS. 15 to 18 inclusive. The electric eye unit comprises a light source 330, and a pickup unit 332 to receive a light beam 336 through a light beam opening 334 of the pickup unit for the purpose of electronically controlling the cutting of the strip 20-26 into individual wrappers 22-28 by sensing the position of index marks 333 (which bear predetermined relations to labels 335 on the overwrap strip 26 as shown in FIG. 16). We have provided mounting means for the light source and pickup however which is novel with respect to arranging it so that either transmitted light as in FIG. 17 or reflected light as in FIG. 18 may actuate the pickup unit.

The mechanism just referred to comprises a clamp bracket 338 secured to part of the frame of the wrapping machine indicated at 340 and carrying a supporting rod 342. A supporting bracket 344 is in turn carried by the rod 342 and the light source 330 is provided with a mounting plate 346 positioned thereagainst. A wrapper support 348 is provided having a light beam opening 349 therein and a mounting foot 350. The mounting foot is clamped to the supporting bracket 344 by a clamp bolt 354 which also cooperates with a spacer 352 and the mounting plate 346 to clamp them in various adjusted positions.

The pickup unit 332 is provided with a mounting bracket 356 which is clamped by means of a clamp bolt 358 to the plate 346 and bracket 344. The bracket is provided with a slot 360 for this purpose through which both of the clamp bolts 354 and 358 extend as illustrated in FIGS. 17 and 18. Also as here illustrated the pickup unit 332 may be adjusted to a position below the wrapper support 348 for transmitted light, or above it and the wrapping material 20-26 to sense reflected light. In the latter case the light source may be tipped for projecting the light beam 336 at an angle suitable for reflection into the pickup unit 332 when adjusted as shown in FIG. 18.

After leaving the electric eye mechanism E the strips 20 and 26 of wrapping material pass between a supporting roller 362 and a feed roller 364 shown in FIG. 32 to a stationary cutoff knife 366 and a rotary cutoff

knife 368. The knife 368 is mounted on an arbor 370 having spaced flanges 372 to contact the overwrap material 26 before it is cut to individual overwraps 30. The knives 366 and 368 also simultaneously cut the strip 20 into individual wrappers 28. The arbor 370 is mounted on a shaft 374 driven from a chain 376 as shown in FIG. 7 which in turn is driven from the shaft 108 that is rotated once each cycle of operation of the wrapping machine. The feed roller 364 however is driven from a chain 376 through a variable speed drive 380 and a wrapper speed-up and retard mechanism 382 by means of a belt 384. The variable speed drive 380 may be adjusted for approximately the correct speed of feed for the roller 362 so that this roller acts as a measuring means for the wrappers, and the mechanism 382 effects the final adjustment in response to the electric eye E as shown in the Sandberg patents. In FIGS. 4, 29 and 31, a timing chain, adjusting means 373 and adjusting knob 375 therefor are also shown for the electric eye mechanism as also disclosed in the Sandberg patents.

An anvil 386 precedes the supporting roller 362 and carries a scraper blade 388 therefor. A holding bar 390 is provided opposite the anvil which is normally spaced to permit free passage of the strips 20 and 26. The bar 390 is supported by a pair of levers 389 pivoted at 391. Extensions 393 of the levers 389 are connected to plungers of solenoids 392 that are automatically energized to stop wrapper feed by gripping the wrapping strip 20-26 and at the same time lifting the roller 364 carried by the levers 389 on that side of the pivot 391 opposite the bar 390. Throw-out adjustment for the pivot 391 is had by levers 396 terminating in handles 398, one for each side of the machine as shown in FIG. 29. The levers 396 are provided with eccentrics 395 to effect elevation of the wrapper feed roller 364 and the holding bar 390 to permit entry of the wrapping material into the wrapper feeding mechanism.

After leaving the cutoff knives 366 and 368 the individual wrappers 28-30 are carried by a pair of wrapper feed belts 400 to the position B shown in FIG. 13 and against a stop 402. When the wrappers engage the stop the belts slip under them. Opposing the belts 400 as shown in FIG. 32 are weighted hold-down rollers 404. There are three of these rollers for each of the two belts 400 and each roller is mounted on an arbor that floats vertically in a cage 401. The six cages are slidable longitudinally in two channels 403 each having a slot 405 through which two clamp screws 406 for each cage extend and thread into the cages. Thus the cages may be spaced along the wrapper as found most advantageous.

A pulley 408 is provided for one end of each of the wrapper feed belts 400 as shown in FIGS. 13, 30 and 32, and pulleys 410 are provided for the other ends thereof as shown in FIG. 13. The two belts are horizontally on opposite sides of a rectangular chute 412 shown in FIG. 13 into which the elevator posts 302 extend during the wrapping operation. Idler rollers such as shown at 414 also cooperate with the belts 400 to control their return stretches so that they are relatively close to the upper delivery stretches thereof as illustrated in FIG. 13. The belts 400 are driven from the chain 376 which drives a countershaft 604 (see FIGS. 7 and 29) connected by a belt 606 to the pulleys 408. The wrapper feed belts 400 and the hold-down rollers 404 being provided in two sets are adjustable as to spacing apart by means of a right and left hand adjusting screw 416 shown in FIG. 29 controlled by a hand wheel 418.

Referring particularly to FIGS. 8, 9, 10, 13 and 14, the folding way indicated by the bracket F in FIGS. 1, 13 and 14 and is associated mechanism is illustrated. A rectangular folding chute is provided comprising walls 420 and 422 shown in FIG. 13 and walls 424 and 426 shown in FIG. 14. The walls 420 and 422 are provided with the usual folding wings 428 and 430 for folding the end flaps 32 shown in FIG. 1 after the ends of the

wrapper are folded down by the walls 420 and 422 as the product and wrapper are elevated through the folding way F, again in substantially the same manner as shown in the Sandberg patents. When the partially wrapped package reaches the position C shown in FIG. 13 it engages stops 431 pivoted at 433 and spring-biased to the position shown by springs 435. The stops prevent excessive travel of the package due to rather fast elevation thereof through the folding way and may be raised against the spring bias if the product is exceptionally thick. They may also be swung up to a vertical position for clearing the machine of a damaged package or in case of other malfunctioning. Tucker blades 432 and 434 then tuck the end flaps 32 under the package as indicated by the arrows 34 and 36 respectively in FIGS. 1 and 13 after which a tucker blade 436 tucks the flap 30 under the package as indicated by the arrow 38 in FIGS. 1 and 14. Actually all three tucking operations indicated by the arrows 34, 36 and 38 are at the same position C whereas two separate illustrations are shown for this position in FIG. 1 to illustrate the successive operations 34 and 36 together, and thereafter 38, all at the one station C. These operations likewise are similar to those carried out in the Sandberg wrapping machines shown in the patents above referred to. However we have designed the mountings for the folding way walls and the tucker blades to permit adjustment thereof so that the machine can be readily adjusted for a great range of sizes of product.

To support the product and wrapper while the elevator posts 302 retract, a rock shaft 438 shown in FIG. 14 is provided to which is secured a supporting lever 440 terminating in a supporting pad 442. The folding way wall 424 is provided with an opening 444 through which the pad and arm extend when swinging about one-fourth revolution counter-clockwise from the position shown in FIG. 14.

The constructional features permitting of adjustment as above referred to are as follows:

The walls 424 and 426 are connected together by a pair of upper spacers 446 and lower spacers 448 (see FIG. 13), and are provided with notches 450 to fit down over supporting rods 452 which in turn are supported by brackets 454 shown in FIG. 9. Other assemblies of walls 424 and 426 may thus be substituted which assemblies have the walls spaced farther apart or closer together as required. Each assembly has its own set of walls 420 and 422 and they are supported by rods 456 as shown in FIG. 13 adjustable in blocks 457 for changing the distance between the walls 420 and 422 as required.

The tucker blades 432 and 434 are pivoted at 458 and 460 to carrying brackets 462 and 464 respectively. The bracket 462 is clamped to a slide rod 466 whereas the bracket 464 is slidable on the rod, and the two brackets are simultaneously slid in opposite directions by a rock shaft 468 to which is secured a rock lever 470 to which links 472 and 476 are pivoted. The link 472 is also pivoted to a bracket 474 secured to the slide rod 466, whereas the link 476 is pivoted to the pivot 460 of the bracket 464. The tucker blades 432 and 434, in addition to traveling toward each other to tuck the end flaps 32 are raised to press against the bottom of the partially wrapped package by means of rollers 478 (see FIG. 8) contacting cam surfaces 481 on the bottoms of cam rods 480, springs 482 being provided to bias the rollers into contact with the cams. The cam rods are adjustable with respect to stationary bosses 484 on the frame of the machine, and one of the cam surfaces is shown dotted at 481 in FIG. 13. The tucker blades 432 and 434 are disconnectable with respect to the brackets 462 and 464, latch pins 486 being provided for this purpose. The tucker blade 436 is disconnectable with respect to the bracket 530, headed pins 447 and coacting keyhold slots 449 (see dotted in FIG. 8) being provided for this purpose. Accordingly wider or narrower blades

432, 434 and 436 may be quickly substituted as required.

The strokes of the tucker blades 432 and 434 are adjustable by the mechanism shown in FIG. 10. The rock shaft 468 it will be noted has a crank arm 488 thereon adapted to be oscillated by a rock arm 490 pivoted to the arm 488 at 492. The rock arm 490 in turn has a stud 494 carried by an adjustable block 496. A block 495 is rotatable on the stud 494 and travels in a roller way 497 of the rock arm 490. The roller way comprises upper and lower flanges secured to the top and bottom edges of the arm 490. An adjusting screw 498 is threaded in the block 496, the unthreaded ends thereof being journaled in bearings 500 of a stationary bracket 502 (see also FIG. 9). The bracket 502 is secured to a cross member 504 of the frame of the machine by three screws 505. The adjusting screw 498 is held against longitudinal movement relative to the bearings 500 by a collar 506 and a hand wheel 508, the hand wheel being also operable for adjusting the block 496 and thereby the stud 494 and roller 495 along the roller way 497. The roller 495 is thus adaptable to assume various positions longitudinally of the rock arm 490 and relative to its pivot 492, and relative to a second pivot 510 with which the upper end of a link 512 is connected.

The link 512 extends downwardly as shown in FIG. 9 and its lower end as illustrated in FIG. 11 is pivoted to an arm 514 which is also shown in FIGS. 12 and 35. A sleeve 515 extends from the lever 514 through a bearing 517 at the right side of the transmission housing 290 shown in FIG. 35 and terminates in a cam lever 518 carrying a cam roller 520. The cam roller coacts with a suitable cam groove in the right hand face of an end flap cam 522 on the cam shaft 318.

A similar arrangement is provided for reciprocating the tucker blade 436 in FIGS. 8, 9 and 14 and comprises a rock shaft 524 comparable to the rock shaft 468 of FIG. 10 but arranged at right angles thereto. The rock shaft 524 is operably connected to the tucker blade 436 by means of a lever 526 connected by a link 528 pivoted at 529 to a bracket 530 that slides on a guide rod 552, the blade 436 being pivoted thereto at 437. The rock shaft 524 has secured thereto a rock arm 534 shown in FIGS. 8 and 9 with which the upper end of a link 536 is pivotally connected. The lower end of the link 536 is pivotally connected to an arm 538 mounted on a shaft 516 (FIG. 35) which may rock in the sleeve 515 and has on its inner end a cam lever 540 carrying a cam roller 542. The cam roller travels in a suitably shaped cam groove in the left face of a tucker cam 544 on the cam shaft 318 as shown in FIG. 35.

Referring to FIG. 8, the rock arm 534 is of the same adjustable leverage type as the rock arm 490, comparable parts that can be seen being numbered 488^a, 492^a and 497^a. Thus the stroke of the tucker blade 436 is adjustable in a like manner to the tucker blades 432 and 434. The blade 436 is also adapted to be elevated by rocking on the pivot 437, an extension arm 439 (FIG. 14) for the blade being provided for this purpose. The arm carries a cam roller 441 contacting a cam surface 443 of a stationary cam bar 445.

After the operation of the tucker blade 436 the package P is completed and can then be pushed off the supporting pad 442 which at that time is within the folding way and adjacent position C in FIG. 14, the direction of push being toward the left as indicated by the arrow 546. A pusher 548 is provided for this purpose which is mounted on the left hand end of a slide rod 522 carried by a bracket 550 slidable on stationary guide rod 532 supported by a bracket 533. The bracket 550 in turn is connected by a link 554 pivoted to a rock arm 556 which in turn is secured to a rock shaft 558. The rock shaft as shown in FIG. 8 has a lever 560 secured thereto and the upper end of a link 562 is pivoted to the lever. The lower end of the link is pivoted to a lever 564 (see

FIG. 11) which as shown in FIG. 35 is secured to the outer end of a sleeve 566 extending through a bearing 568 at the left side of the transmission housing 290 and terminating within the housing in a cam lever 570. The lever 570 carries a cam roller 572 which travels in a suitable cam groove in the left face of a pusher cam 574 on the cam shaft 318.

The rock shaft 438 for the supporting lever 440 and its supporting pad 442 of FIG. 14 is also shown in FIG. 8. On its left hand end the rock shaft carries a rock arm 576 to which the upper end of a vertical link 578 is pivoted, the lower end of the link being shown in FIG. 11 pivoted to a lever 580. As shown in FIG. 35 the lever 580 is connected to a shaft 582 extending through the sleeve 566 and terminating in a cam lever 584 carrying a cam roller 586. The roller 586 is received in a suitably shaped cam groove in the right hand face of a supporting pad cam 588, also on the cam shaft 318. As the completed packages P are pushed from the position C in FIGS. 1 and 14 by the pusher 548 as indicated by the arrow 546 they cross a stationary platform 590 and are deposited on a woven wire belt 592 of a take-away conveyor.

Take-Away Conveyor

The belt 592 traverses rollers 594 and 596 (see also FIGS. 38, 39 and 40) and pass over electric heater units 598 and 600 which "set" the folded flaps of the package which may be paraffin-impregnated, or provided with a suitable heat settable glue at advantageous points on the wrapping material. The belt 592 also passes over an idler roller 601. The completed packages P are picked up by a discharge belt 602 from which they may be discharged or picked up for cartoning as desired.

The drive means for the belt 592 comprises a drive shaft 597 for the roller 596. A belt 608 is driven from a pulley 609 on the shaft 597 and drives a pulley 611 on a shaft 640 having a drum 642 for the belt 602. As shown in FIG. 41, the shaft 640 is journaled in a box-like frame member 610 which is supported by a pair of brackets 613 (see FIG. 5) on the main frame of the machine.

We also provide holdown belts 614 for the packaged product P as shown in FIG. 40 which extend around pulleys 616 and 618 as shown in FIG. 38 and are biased downwardly by shoes 620 carried by pivoted arms 622 connected with springs 624. The belts 614 are driven by pulleys 626 (see FIG. 41) on a shaft 628 provided with a gear 630 meshing with a gear 632. The gear 632 is on a vertical shaft 634 having a gear 636 meshing with a gear 638 on the shaft 640 that is driven by the belt 608 from the drive shaft 597, the driving means for which will be later described.

The belts 614 and the shoes 620 provide two spaced hold-down units as illustrated in FIGS. 39 and 41 which are adjustable toward and away from each other for different sizes of packaged product by means of two right and left hand adjusting screws 644. The screws are provided with sprockets 646 connected together by a chain 648 for simultaneous adjustment. Each of the screws has a hand wheel 650, either of which may be manipulated for adjustment purposes.

As shown in FIG. 41 the hold-down assembly is also vertically adjustable by reason of being carried by a pair of bosses 652 slidable on vertical posts 654 at the upper end of which is journaled a rock shaft 656. On the rock shaft are chain sectors 658 with which the upper ends of chains 660 are connected, the lower ends of the chains being connected to the bosses 652. An adjusting lever 662 is provided for rocking the shaft 656, and the shaft may be locked at the adjusted position by a clamp lever 664.

The drive shaft 597 is driven by a speed reducer 651 having in-put shaft on which is a variable speed pulley 655. This pulley is driven by a belt 657 from a motor

659 and has an adjuster 661 for the pulley speed (see FIGS. 4, 5 and 39).

From the construction of the parts just described it is obvious that the take-away conveyor has a number of desirable features. Its speed is variable over a wide range (pulley 655) independently of the wrapping machine. Also temperatures are variable by controlling the voltage supplied to the heater units 609. Thus widely varying sizes of packages and different types of wrapping materials are accommodated. Pressure of the shoes 620 is also variable. Thus the exact time, temperature and pressure is available to effect a perfect seal on a wide range of packages. The belt 592 under the package and the pressure belt 614 on top of it and traveling at the same linear speed prevents any smearing of the under seal of the package (next to the woven wire belt 592), thus allowing advertising to be printed on the bottom panel of the package. This has not been commonly done heretofore because of such smearing.

Referring to FIGS. 27 and 28 a safety switch 666 with a no-product switch 668 are illustrated. As shown in FIG. 23 these are located adjacent the lower right corner of the figure just prior to the position D from which pusher 224 pushes the card 14 and product 17 (arrow 21) to position A as depicted in FIG. 1. The switch 666 is mounted on a bracket 670 secured to one of the platforms 224 and the switch 668 is also suitably secured thereto. The switch 666 is operated by a tubular rock shaft 672 provided with product sensing fingers 674. If the product P has one end up on a card moving pin 161, or if the product is on its side in front of a pin 161, its top surface will be unduly elevated and strike the sensing fingers 674 to operate the switch 666 which effects stoppage of the machine.

The switch 668 is operated by a switch operating lever 676 which is actuated by a switch actuating lever 678 pivoted at 680 and carrying a bracket 682 provided with a contact screw 684 to engage the lever 676. This switch has a no-product position determined by the spring 677 which elevates the switch actuating lever 678 to the position shown in FIG. 28 away from a stop screw 686. While there is a continuous flow of product past the position D in FIG. 23 the weight of the product will depress the lever 678 to move the switch 668 to open position. When one or more units of product are missing from between the pins 161, the switch 668 will close, thereby energizing the solenoids 392 which will stop the feeding of wrapped material.

Inasmuch as the operation of the various parts of our wrapping machine have been described along with the detailed description of the parts of the machine, its overall operation is believed obvious, especially in conjunction with the initial general description of the operation as related to FIG. 1.

Some changes may be made in the construction and arrangement of the parts of our wrapping machine without departing from the real spirit and purpose of our invention, and it is our intention to cover by our claims any modified forms of structure or use of mechanical equivalents which may reasonably be included within their scope.

We claim as our invention:

1. In a wrapping machine of the character disclosed, card feeding and cutting, and boat forming mechanism comprising an arbor for a roll of cardboard from which the cardboard may be withdrawn, means for withdrawing cardboard from the roll of cardboard and scoring the same, said scoring means comprising a pair of scoring rolls and a pair of hold-down rolls cooperating therewith, means for adjusting the distance apart thereof comprising a pair of nuts, an adjusting shaft having opposite pitched threads on which said nuts are threaded and groove-and-flange connections between said scoring rolls, hold-down rolls and said nuts, cutoff means for the cardboard to cut it into cards, forming means for the cards to form them into channel-shaped boats comprising plows for bending

up side flanges beyond the score lines of the card, hold-down flanges engaging the tops of the cards adjacent the scored lines and cooperating with said plows in forming the flanges of the boat, means for adjusting the distance apart of said plows and said hold-down flanges independently of each other comprising an adjusting shaft for each having opposite pitched threads and a nut on each thread operatively connected with said plows and hold-down flanges, a transfer conveyor for receiving the boat from said boat-forming means, said transfer conveyor having spaced projections for spacing the boats on the conveyor, a pair of feed stations on opposite sides of said transfer conveyor at which alternate boats may be fed with product, said transfer conveyor delivering the boats with product thereon to a designated station on said transfer conveyor, a pusher for pushing the boat and product from said designated station to another station, wrapper feeding and cutting mechanism for feeding a strip of wrapping material, cutting the same into wrappers and delivering the wrappers to a position over said another station, said wrapper feeding mechanism having electric eye means controlling said cutting mechanism to vary the length of the wrappers, said electric eye means including light beam mechanism cooperating with patterns on the wrapper material, said light beam mechanism having a unit which is adjustable to either face of the wrapper for transmitted light when on the opposite side of the wrapper from the light source, and for reflected light when adjusted to the same side thereof, a folding way above said another station, wrapper tucking blades adjacent three sides of said folding way to tuck three flaps of the wrapper under the boat and product, two of said tucking blades being opposite each other and interconnected for simultaneous movement in opposite directions, a crank arm for effecting such movement, a lever having one end pivoted to said crank arm, a reciprocable actuator pivoted to the other end of said arm, pivot means for said arm intermediate the ends thereof, means for adjusting said pivot means along said arm to vary the stroke of said crank arm and thereby said two of said tucking blades, said last means comprising an adjusting screw cooperating with said pivot means, means for pushing the partially wrapped package from said folding way and thereby folding the remaining flap of the package, a take-away conveyor adapted to receive the wrapped package from said folding way, said take-away conveyor having a belt for the wrapped packages, heat-sealing mechanism over which said belt conveys the packages and operable to heat-seal the flaps thereof, and hold-down belts for the packages located above said woven wire belt, means for adjusting said hold-down belts toward and away from each other for different widths of product, said last means comprising a pair of adjusting shafts having opposite pitched threads, nuts threaded thereon and operatively connected with said hold-down belts and means connecting said adjusting shafts together for simultaneous operation, and means for adjusting said hold-down belts upwardly and downwardly for different thicknesses of product.

2. In a wrapping machine of the character disclosed, card feeding and cutting, and boat forming mechanism comprising an arbor for a roll of cardboard from which the cardboard may be withdrawn, means for withdrawing cardboard from the roll of cardboard and scoring the same, cutoff means for the cardboard to cut it into cards, forming means for the cards to form them into channel-shaped boats comprising plows for bending up side flanges beyond the score lines of the card, hold-down flanges engaging the tops of the cards adjacent the scored lines and cooperating with said plows in forming the flanges of the boat, means for rapidly projecting the boat after it is formed away from said boat forming mechanism, a transfer conveyor for receiving the boat from said projecting means, said transfer conveyor turning the boats 180°, carrying them away from the machine and then toward it again, a pair of feed stations on opposite sides of said transfer conveyor at which alternate boats may be fed with product, said transfer conveyor delivering the boats with product thereon to a designated station on said transfer conveyor, a pusher for pushing the boat and product

from said designated station to another station offset relative to said rapid projecting means, said transfer conveyor spanning the offset distance, wrapper feeding and cutting mechanism for feeding a strip of wrapping material, cutting the same into wrappers and delivering the wrappers to a position over said another station, said wrapper feeding mechanism having electric eye means controlling said cutting mechanism to vary the length of the wrappers, said electric eye means including light beam mechanism cooperating with patterns on the wrapper material, said light beam mechanism having a unit which is adjustable to either face of the wrapper for transmitted light when on the opposite side of the wrapper from the light source, and for reflected light when adjusted to the same side thereof, a folding way above said another station, wrapper tucking blades adjacent three sides of said folding way to tuck three flaps of the wrapper under the boat and product, two of said tucking blades being opposite each other and interconnected for simultaneous movement in opposite directions, a crank arm for effecting such movement, a lever having one end pivoted to said crank arm, a reciprocable actuator pivoted to the other end of said arm, pivot means for said arm intermediate the ends thereof, means for adjusting said pivot means along said arm to vary the stroke of said crank arm and thereby said two of said tucking blades, said last means comprising an adjusting screw cooperating with said pivot means, means for pushing the partially wrapped package from said folding way and thereby folding the remaining flap of the package, a take-away conveyor adapted to receive the wrapped package from said folding way, said take-away conveyor having a belt for the wrapped packages, heat-sealing mechanism over which said belt conveys the packages and operable to heat-seal the flaps thereof, and hold-down belts for the packages located above said belt.

3. In a wrapping machine of the character disclosed, card feeding and cutting mechanism comprising means to hold a roll of cardboard from which the cardboard may be withdrawn whereupon the roll will rotate, a spider-like side for said roll, said side being adjustable with respect to said arbor to accommodate different widths of cardboard, means for withdrawing cardboard from the roll of cardboard, opposed roller means for crimping opposite side edges thereof to stiffen the cardboard, cutoff means for the cardboard to cut it into cards, means for rapidly projecting the card away from said cutoff mechanism, a card transfer conveyor for receiving the card from said projecting means, said transfer conveyor having spaced projections for spacing the cards on the conveyor, said transfer conveyor turning the cards 180°, a pair of feed stations adjacent said transfer conveyor at which alternate cards may be fed with product, said transfer conveyor delivering the cards with product thereon to a designated station on said transfer conveyor, a pusher for pushing the card and product from said designated station to another station offset relative to said rapid projecting means, said transfer conveyor spanning the offset distance, wrapper feeding and cutting mechanism for feeding the strip of wrapping material, cutting the same into wrappers and delivering the wrappers to a position over said another station, said wrapper feeding mechanism having electric eye means controlling said cutting mechanism and including light beam mechanism cooperating with patterns on the wrapper material, said light beam mechanism having a unit which is adjustable to either face of the wrapper for transmitted light when on the opposite side of the wrapper from the light source, and for reflected light when adjusted to the same side thereof, a folding way above said another station, said folding way being adjustable as to width and length, wrapper tucking blades adjacent three sides of said folding way to tuck three flaps of the wrapper under the card and product, said tucker blades being readily replaceable with others of different width, lever means for reciprocating said tucker blades, said lever means being of adjust-

able length to vary the strokes of said blades, means for pushing the partially wrapped package from said folding way and thereby folding the remaining flap of the package, a take-away conveyor adapted to receive the wrapped package from said folding way, said take-away conveyor having a woven wire belt for the wrapped packages, heat-sealing mechanism over which said belt conveys the packages and operable to heat-seal the flaps thereof, and hold-down belts for the packages located above said woven wire belt, said hold-down belts being adjustable toward and away from each other for different widths of product, and upwardly and downwardly for different thicknesses thereof.

4. In a wrapping machine of the character disclosed, card feeding and cutting mechanism comprising means to hold a roll of cardboard from which the cardboard may be withdrawn, means for withdrawing cardboard from the roll of cardboard, cutoff means for the cardboard to cut it into cards, a card transfer conveyor for receiving the card from said cutoff means, said transfer conveyor having spaced projections for spacing the cards on the conveyor, said transfer conveyor turning the cards 180°, a pair of feed stations adjacent said transfer conveyor at which product is deposited on alternate cards, said transfer conveyor delivering the cards with product thereon to a designated station on said transfer conveyor, a pusher for pushing the card and product from said designated station to another station, wrapper feeding and cutting mechanism for feeding a strip of wrapping material, cutting the same into wrappers and delivering the wrappers to a position over said another station, said wrapper feeding mechanism having electric eye means controlling said cutting mechanism, a folding way above said another station, said folding way being adjustable as to width and length, wrapper tucking blades adjacent three sides of said folding way to tuck three flaps of the wrapper under the boat and product, said tucker blades being readily replaceable with others of different width, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, heat-sealing mechanism for the packages and operable to heat-seal the flaps thereof, and hold-down belts for the packages located above said take-away conveyor, said hold-down belts being adjustable toward and away from each other for different widths of product, the means for effecting such adjustment comprising a pair of adjusting shafts having opposite pitched threads, nuts threaded thereon and operatively connected with said hold-down belts and means connecting said adjusting shafts together for simultaneous operation, and means for adjusting said hold-down belts upwardly and downwardly for different thicknesses of product.

5. In a wrapping machine, card feeding and cutting, and boat forming mechanism comprising an arbor adapted to hold a roll of cardboard from which the cardboard may be withdrawn, means for withdrawing cardboard from the roll of cardboard and scoring the same, said scoring means comprising a pair of scoring rolls and means for adjusting the distance apart thereof comprising a pair of nuts, an adjusting shaft having opposite pitched threads on which said nuts are threaded and groove-and-flange connections between said scoring rolls and said nuts, cutoff means for the cardboard to cut it into cards, forming means for the cards to form them into channel-shaped boats comprising plows for bending up side flanges beyond the score lines of the card, motor and roller means for rapidly projecting the boat after it is formed away from said boat forming mechanism, a transfer conveyor for receiving the boat from said projecting means, said transfer conveyor having spaced projections for spacing the boats on the conveyor, said

transfer conveyor turning the boats 180°, carrying them away from the machine and then toward it again, a feed station adjacent said transfer conveyor at which product is deposited on said boats, said transfer conveyor delivering the boats with product thereon to a designated station on said transfer conveyor, a pusher for pushing the boat and product from said designated station to another station offset from said motor and roller means, said transfer conveyor spanning the offset distance, wrapper feeding and cutting mechanism for feeding a strip of wrapping material, cutting the same into wrappers and delivering the wrappers to a position over said another station, said wrapper feeding mechanism being adjustable to accommodate different widths of wrapping material and having electric eye means controlling said cutting mechanism to vary the length of the wrappers, a folding way above said another station, said folding way being adjustable as to width and length, wrapper tucking blades adjacent three sides of said folding way to tuck three flaps of the wrapper under the boat and product, said tucker blades being readily replaceable with others of different width, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, said take-away conveyor having a woven wire belt for the wrapped packages, heat-sealing mechanism over which said belt conveys the packages and operable to heat-seal the flaps thereof, and hold-down belts for the packages located above said woven wire belt.

6. In a wrapping machine, card feeding and cutting mechanism comprising means adapted to hold a roll of cardboard from which the cardboard may be withdrawn, a spider-like side for said roll, said side being adjustable to accommodate different widths of cardboard, means for withdrawing cardboard from the roll of cardboard, cutoff means for the cardboard to cut it into cards, a transfer conveyor receiving cards from said cutoff means and delivering them to a designated station, a feed station adjacent said transfer conveyor at which product is deposited on said cards, a pusher for pushing cards loaded with product from said designated station to another station, wrapper feeding and cutting mechanism for feeding a strip of wrapping material, cutting the same into wrappers and delivering the wrappers to a position over said another station, said wrapper feeding mechanism being adjustable to accommodate different widths of wrapping material, the adjusting means therefor comprising a pair of wrapper feed belts, hold-down rollers opposing said belts, a pair of frame members carrying said belts and rollers and an adjusting shaft having opposite pitched threads coating with said frame members to simultaneously adjust them toward or away from each other, said wrapper feed mechanism having electric eye means controlling said cutting mechanism to vary the length of the wrappers, said electric eye means including light beam mechanism cooperating with patterns on the wrapper material, a folding way above said another station, said folding way being adjustable as to width and length, wrapper tucking blades adjacent three sides of said folding way to tuck three flaps of the wrapper under the card and product, means for pushing the partially wrapped package from said folding way and thereby folding the remaining flap of the package, a take-away conveyor adapted to receive the wrapped package from said folding way, said take-away conveyor having a woven wire belt for the wrapped packages, heat-sealing mechanism over which said belt conveys the packages and operable to heat-seal the flaps thereof, and hold-down belts for the packages located above said woven wire belt, said hold-down belts being adjustable upwardly and downwardly for different thicknesses of product.

7. In a wrapping machine of the character disclosed,

card feeding and cutting, and boat forming mechanism comprising means for withdrawing cardboard from a roll of cardboard and scoring the same, said scoring means comprising a pair of scoring rolls and means for adjusting the distance apart thereof, cutoff means for the cardboard to cut it into cards, forming means from the cards to form them into channel-shaped boats comprising plows for bending up side flanges beyond the score lines of the card, hold-down flanges engaging the tops of the cards adjacent the scored lines and cooperating with said plows in forming the flanges of the boat, means for adjusting the width between said flanges and the distance apart of said plows independently of each other comprising an adjusting shaft for each having opposite pitched threads and a nut on each thread operatively connected with said plows and hold-down flanges, a transfer conveyor receiving boats from said boat forming mechanism and delivering them to a designated station, a feed station adjacent said transfer conveyor at which product is deposited on said boats, a pusher for pushing boats loaded with product from said designated station to another station, wrapper feeding and cutting mechanism for feeding a strip of wrapping material, cutting the same into wrappers and delivering the wrappers to a position over said another station, said wrapper feeding mechanism being adjustable to accommodate different widths of wrapping material and having electric eye means controlling said cutting mechanism to vary the length of the wrappers, said electric eye means including light beam mechanism cooperating with patterns on the wrapper material, said light beam mechanism having a unit which is adjustable to either face of the wrapper for transmitted light when on the opposite side of the wrapper from the light source, and for reflected light when adjusted to the same side thereof, a folding way above said another station, wrapper tucking blades adjacent three sides of said folding way to tuck three flaps of the wrapper under the card or boat and product, said tucker blades being readily replaceable with others of different width, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, said take-away conveyor having a belt for the wrapped packages, heat-sealing mechanism over which said belt conveys the packages and operable to heat-seal the flaps thereof, and hold-down means for the packages located above said belt, said hold-down means having a frame adjustable upwardly and downwardly for different thicknesses of product and the adjusting means therefor comprising a rockshaft extending longitudinally of said belt, a pair of disk segments secured to said shaft, a pair of chains each secured at one of its ends to one of said disk segments and at its other end to said frame, and means for locking said rockshaft against rotation.

8. In a wrapping machine card feeding and cutting, and boat forming mechanism comprising an arbor adapted to hold a roll of cardboard from which the cardboard may be withdrawn, means for withdrawing cardboard from the roll of cardboard and scoring the same, said scoring means comprising a pair of scoring rolls, cutoff means for the cardboard to cut it into cards, forming means for the cards to form them into channel-shaped boats comprising plows for bending up side flanges beyond the score lines of the card, hold-down flanges engaging the tops of the card adjacent the scored lines and cooperating with said plows in forming the flanges of the boat, a transfer conveyor for receiving the boat from said boat forming means, said transfer conveyor having spaced projections for spacing the boats on the conveyor, said transfer conveyor carrying the boats past a pair of feed stations on opposite sides of the conveyor at which alternate boats may be fed with product, said transfer conveyor deliver-

ing the boats with product thereon to a designated station, a pusher for pushing the boat and product from said designated station to another station, wrapper feeding and cutting mechanism for feeding a strip of wrapping material, cutting the same into wrappers and delivering the wrappers to a position over said another station, a folding way above said another station, means for elevating a boat, product and a wrapper through said folding way, tucking the flaps thereof and pushing the package from said folding way, a take-away conveyor adapted to receive the wrapped package from said folding way, said take-away conveyor having a woven wire belt for the wrapped packages, heat-sealing mechanism over which said take-away conveyor conveys the packages and operable to heat-seal the flaps thereof, and hold-down belts for the packages located above said take-away conveyor, means for adjusting said hold-down belts toward and away from each other for different widths of product, said last means comprising a pair of adjusting shafts having opposite pitched threads, nuts threaded thereon and operatively connected with said hold-down belts and means connecting said adjusting shafts together for simultaneous operation, and for adjusting said hold-down belts upwardly and downwardly for different thicknesses of product comprising a rockshaft extending longitudinally of said belt, a pair of disk segments secured to said shaft, a pair of chains each secured at one of its ends to one of said disk segments and at its other end to said frame, and means for locking said rockshaft against rotation.

9. In a wrapping machine, card feeding and cutting, and boat forming mechanism comprising an arbor adapted to hold a roll or cardboard from which the cardboard may be withdrawn whereupon the roll will rotate said arbor, friction means to restrain such rotation, means for withdrawing cardboard from the roll of cardboard and scoring the same, said scoring means comprising a pair of scoring rolls, cutoff means for the cardboard to cut it into cards, forming means for the cards to form them into channel-shaped boats comprising plows for bending up side flanges beyond the score lines of the card, motor and roller means for rapidly projecting the boat after it is formed away from said boat forming mechanism, a transfer conveyor for receiving the boat from said projecting means, said transfer conveyor turning the boats 180° and carrying them past a pair of feed stations on opposite sides of the conveyor at which alternate boats may be fed with product, said transfer conveyor delivering the boats with product thereon to a designated station, a pusher for pushing the boat and product from said designated station to another station offset relative to said rapid projecting means, said transfer conveyor spanning the offset distance, wrapper feeding and cutting mechanism for feeding a strip of wrapping material, cutting the same into wrappers and delivering the wrappers to a position over said another station, a folding way above said another station, means for elevating a boat, product and a wrapper through said folding way, tucking the flaps thereof and pushing the package from said folding way, a take-away conveyor adapted to receive the wrapped package from said folding way, heat-sealing mechanism over which said take-away conveyor conveys the packages and operable to heat-seal the flaps thereof, and hold-down belts for the packages located above said take-away conveyor, said hold-down belts having a frame adjustable upwardly and downwardly for different thicknesses of product and the adjusting means therefor comprising a rockshaft extending longitudinally of said belt, a pair of disk segments secured to said shaft, a pair of chains each secured at one of its ends to one of said disk segments and at its other end to said frame, and means for locking said rockshaft against rotation.

10. In a wrapping machine of the character disclosed, card feeding and cutting, and boat forming mechanism comprising means adapted to hold a roll of cardboard from which the cardboard may be withdrawn, means for

withdrawing cardboard from the roll of cardboard and scoring the same, said scoring means comprising a pair of scoring rolls, cutoff means for the cardboard to cut it into cards, forming means for the cards to form them into channel-shaped boats, means for rapidly projecting the boat after it is formed away from said boat forming mechanism, a transfer conveyor for receiving the boat from said projecting means, said transfer conveyor having spaced projections to stop the projected motion of the boats from said projecting means, said projections spacing the boats on the conveyor, said transfer conveyor carrying the cards past a pair of feed stations at which alternate boats may be fed with product, said transfer conveyor delivering the boats with product thereon to a designated station, a pusher for pushing the boat and product from said designated station to another station, wrapper feeding and cutting mechanism for feeding a strip of wrapping material, cutting the same into wrappers and delivering the wrappers to a position over said another station, a folding way above said another station, wrapper tucking blades adjacent three sides of said folding way to tuck three flaps of the wrapper under the boat and product, means for reciprocating said tucker blades, means for pushing the partially wrapped package from said folding way thereby folding the remaining flap of the package, and a take-away conveyor receiving finished packages from said folding way, a separate motor for operating said take-away conveyor, and heat-sealing means for the flaps of the packages.

11. In a wrapping machine of the character disclosed, means for supplying boats for supporting product to be wrapped, a transfer conveyor for receiving the boats from said supplying means, said transfer conveyor having spaced projections for spacing the boats thereon, said transfer conveyor delivering the boats with product thereon to a designated station, a feed station adjacent said transfer conveyor at which product is deposited on said boats, a pusher for pushing the boat and product from said designated station to another station, wrapper feeding and cutting mechanism for feeding a strip of wrapping material, cutting the same into wrappers and delivering the wrappers to a position over said another station, said wrapper feeding mechanism comprising a pair of wrapper feed belts, hold-down rollers opposing said belts, a pair of frame members carrying said belts and rollers and an adjusting shaft having opposite pitched threads coating with said frame members to simultaneously adjust them toward or away from each other, said wrapper feeding mechanism having electric eye means controlling said cutting mechanism to vary the length of the wrappers, a folding way above said another station, wrapper tucking blades adjacent three sides of said folding way to tuck three flaps of the wrapper under the boat and product, means for pushing the partially wrapped package from said folding way and thereby folding the remaining flap of the package, a take-away conveyor adapted to receive the wrapped packages from said folding way, said take-away conveyor having a woven wire belt for the wrapped packages, heat-sealing mechanism over which said belt conveys the packages and operable to heat-seal the flaps thereof, and hold-down belts for the packages located above said woven wire belt, said hold-down belts being adjustable toward and away from each other for different widths of product, the adjusting means therefor comprising a pair of adjusting shafts having opposite pitched threads, nuts threaded thereon and operatively connected with said hold-down belts and means connecting said adjusting shafts together for simultaneous operation, and means for adjusting said hold-down belts upwardly and downwardly for different thicknesses of product comprising a rockshaft extending longitudinally of said belt, a pair of disk segments secured to said shaft, a pair of chains each secured at one of its ends to one of said disk segments and at its other end to said frame, and means for locking said rockshaft against rotation.

12. In a wrapping machine of the character disclosed, card feeding and cutting, and boat forming mechanism comprising means to support a roll of cardboard from which the cardboard may be withdrawn, means for withdrawing cardboard from the roll of cardboard and scoring the same, said scoring means comprising a pair of scoring rolls and means for adjusting the distance apart thereof comprising a pair of nuts, an adjusting shaft having opposite pitched threads on which said nuts are threaded and groove-and-flange connections between said scoring rolls and said nuts, cutoff means for the cardboard to cut it into cards, forming means for the cards to form them into channel-shaped boats comprising plows for bending up side flanges beyond the score lines of the card, hold-down flanges engaging the tops of the cards adjacent the scored lines and cooperating with said plows in forming the flanges of the boat, means for adjusting the width between said flanges and the distance apart of said plows independently of each other comprising an adjusting shaft for each having opposite pitched threads and a nut on each thread operatively connected with said plows and hold-down flanges, a transfer conveyor for receiving the boat from said boat forming mechanism, said transfer conveyor having spaced projections for spacing the boats on the conveyor, said transfer conveyor carrying the boats past a pair of feed stations on opposite sides of said transfer conveyor at which alternate boats may be fed with product, said transfer conveyor delivering the boats with product thereon to a designated station, wrapper feeding and cutting mechanism for feeding a strip of wrapping material, cutting the same into wrappers and delivering the wrappers to a position over said station, said wrapper feeding mechanism being adjustable to accommodate different widths of wrapping material, the adjusting means therefor comprising a pair of wrapper feed belts, hold-down rollers opposing said belts, a pair of frame members carrying said belts and rollers and an adjusting shaft having opposite pitched threads coating with said frame members to simultaneously adjust them toward or away from each other, said wrapper feed mechanism having electric eye means controlling said cutting mechanism, a folding way above said designated station, wrapper tucking blades adjacent three sides of said folding way to tuck three flaps of the wrapper under the boat and product, two of said tucking blades being opposite each other and interconnected for simultaneous movement in opposite directions, a crank arm for effecting such movement, a lever having one end pivoted to said crank arm, a reciprocable actuator pivoted to the other end of said arm, pivot means for said arm intermediate the ends thereof, means for adjusting said pivot means along said arm to vary the stroke of said crank arm and thereby said two of said tucking blades, said last means comprising an adjusting screw cooperating with said pivot means, means for pushing the partially wrapped package from said folding way and thereby folding the remaining flap of the package, a take-away conveyor adapted to receive the wrapped package from said folding way, said take-away conveyor having a belt for wrapped packages, heat-sealing mechanism over which said belt conveys the packages and operable to heat-seal the flaps thereof, and hold-down belts for the packages located above said belt.

13. In a wrapping machine of the character disclosed, card feeding and cutting, and boat forming mechanism comprising an arbor adapted to hold a roll of cardboard from which the cardboard may be withdrawn whereupon the roll will rotate said arbor, means for withdrawing cardboard from the roll of cardboard and scoring the same, said scoring means comprising a pair of scoring rolls, cutoff means for the cardboard to cut it into cards, forming means for the cards to form them into channel-shaped boats comprising plows for bending up side flanges beyond the score lines of the card, hold-down flanges engaging the tops of the cards adjacent the scored lines

and cooperating with said plows in forming the flanges of the boat, a transfer conveyor having an intake end aligned with said boat forming mechanism, said transfer conveyor having spaced projections for spacing the boats on the conveyor, said transfer conveyor carrying the boats through an arc of 180° and past a pair of feed stations on opposite sides of said transfer conveyor at which alternate boats may be fed with product, said transfer conveyor having a delivery end laterally spaced from said intake end which delivers the boats with product thereon to a designated station, wrapper feeding and cutting mechanism aligned with said designated station for feeding a strip of wrapping material thereto, cutting the same into wrappers and delivering the wrappers to a position thereover and having electric eye means controlling said cutting mechanism, a folding way above said designated station, said folding way being adjustable as to width and length, wrapper tucking blades adjacent three sides of said folding way to tuck three flaps of the wrapper under the card and product, said tucker blades being readily replaceable with others of different widths, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, said take-away conveyor having a woven wire belt for the wrapped packages, heat-sealing mechanism over which said belt conveys the packages and operable to heat-seal the flaps thereof, and hold-down belts for the packages located above said woven wire belt, said hold-down belts being adjustable toward and away from each other for different widths of product, and upwardly and downwardly for different thickness thereof.

14. In a wrapping machine of the character disclosed, card feeding and cutting, and boat forming mechanism comprising an arbor adapted to hold a roll of cardboard from which the cardboard may be withdrawn, brake means to restrain rotation of said arbor, a side member for the roll of cardboard, said side member being adjustable with respect to said arbor to accommodate different widths of cardboard, means for withdrawing cardboard from the roll of cardboard and scoring the same, said scoring means comprising a pair of scoring rolls and means for adjusting the distance apart thereof, cutoff means for the cardboard to cut it into cards, forming means for the cards to form them into channel-shaped boats comprising plows for bending up side flanges beyond the score lines of the card, means for adjusting the distance apart of said plows comprising a threaded shaft having opposite pitched threads for the respective plows, means for rapidly projecting the boat after it is formed away from said boat forming mechanism, a transfer conveyor receiving boats from said boat forming mechanism and delivering them to a designated station, a feed station adjacent said transfer conveyor at which product is deposited on said boats, a pusher for pushing boats loaded with product from said designated station to another station, wrapper feeding and cutting mechanism for feeding a strip of wrapping material, cutting the same into wrappers and delivering the wrappers to a position over said another station, said wrapper feeding mechanism being adjustable to accommodate different widths of wrapping material and the adjusting means therefor comprising a pair of wrapper feed belts, hold-down rollers in opposition thereto and a threaded shaft having opposite pitched threads for the respective belts and their hold-down rollers, said wrapper feeding mechanism having electric eye means controlling said cutting mechanism to vary the length of the wrappers, said electric eye means including light beam mechanism cooperating with patterns on the wrapper material, a folding way above said another station, means for elevating a boat, product and wrapper through said folding way, tucking the flaps there-

of and pushing the package from said folding way, a take-away conveyor adapted to receive the wrapped package from said folding way, said take-away conveyor having a woven wire belt for the wrapped packages, heat-sealing mechanism over which said belt conveys the packages and operable to heat-seal the flaps thereof, and hold-down belts for the packages located above said woven wire belt, said hold-down belts being adjustable by means of oppositely pitched threaded rods toward and away from each other for different widths of product, and by rock-shaft and chain means upwardly and downwardly for different thicknesses thereof.

15. In a wrapping machine, card feeding and cutting, and boat forming mechanism comprising means adapted to hold a roll of cardboard from which the cardboard may be withdrawn whereupon the roll will rotate, means for withdrawing cardboard from the roll of cardboard and scoring the same, said scoring means comprising a pair of scoring rolls and threaded shaft means having oppositely pitched threads for adjusting the distance apart thereof, cutoff means for the cardboard to cut it into cards, forming means for the cards to form them into channel-shaped boats comprising plows for bending up side flanges beyond the score lines of the card, hold-down flanges engaging the tops of the cards adjacent the scored lines and cooperating with said plows in forming the flanges of the boat, threaded shaft means having oppositely pitched threads for adjusting the width between said flanges, threaded shaft means having oppositely pitched threads for adjusting the distance apart of said plows independent of the adjustment for said flanges, a transfer conveyor receiving boats from said boat forming mechanism and delivering them to a designated station, a feed station adjacent said transfer conveyor at which product is deposited on said boats, a pusher for pushing boats loaded with product from said designated station to another station, wrapper feeding and cutting mechanism for feeding a strip of wrapping material, cutting the same into wrappers and delivering the wrappers to a position over said another station, said wrapper feeding mechanism comprising wrapper feed belts, hold-down rollers opposing said belts, frame members carrying said belts and rollers and an adjusting shaft having opposite pitched threads coacting with said frame members to simultaneously adjust them toward or away from each other to accommodate different widths of wrapping material and having electric eye means controlling said cutting mechanism, coordinating it with patterns on the wrapping material, a folding way above said another station, said folding way being adjustable as to width and length, wrapper tucking blades adjacent three sides of said folding way to tuck three flaps of the wrapper under the boat and product, said tucker blades being readily replaceable with others of different width, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, said take-away conveyor having a woven wire belt for the wrapped packages, heat-sealing mechanism over which said belt conveys the packages and operable to heat-seal the flaps thereof, and hold-down belts for the packages located above said woven wire belt, means for adjusting said hold-down belts toward and away from each other for different widths of product, said last means comprising a pair of adjusting shafts having opposite pitched threads, nuts threaded thereon and operatively connected with said hold-down belts and means connecting said adjusting shafts together for simultaneous operation, and means for adjusting said hold-down belts upwardly and downwardly for different thicknesses of product.

16. In a wrapping machine of the character disclosed, card feeding and cutting, and boat forming mechanism

comprising an arbor adapted to hold a roll of cardboard from which the cardboard may be withdrawn, brake means to restrain rotation of said arbor, a side member for the roll of cardboard, said side member being adjustable with respect to said arbor to accommodate different widths of cardboard, means for withdrawing cardboard from the roll of cardboard and scoring the same, said scoring means comprising a pair of scoring rolls and means for adjusting the distance apart thereof, cutoff means for the cardboard to cut it into cards, forming means for the cards to form them into channel-shaped boats comprising plows for bending up side flanges beyond the score lines of the card, means for adjusting the distance apart of said plows comprising a threaded shaft having opposite pitched threads for the respective plows, means for rapidly projecting the boat after it is formed away from said boat forming mechanism, a transfer conveyor receiving boats from said boat forming mechanism and delivering them to a designated station, a feed station adjacent said transfer conveyor at which product is deposited on said boats, a pusher for pushing boats loaded with product from said designated station to another station, wrapper feeding and cutting mechanism for feeding a strip of wrapping material, cutting the same into wrappers and delivering the wrappers to a position over said another station, said wrapper feeding mechanism being adjustable to accommodate different widths of wrapping material and the adjusting means therefor comprising a pair of wrapper feed belts, hold-down rollers in opposition thereto and a threaded shaft having opposite pitched threads for the respective belts and their hold-down rollers, said wrapper feeding mechanism having electric eye means controlling said cutting mechanism to vary the length of the wrappers, said electric means including light beam mechanism cooperating with patterns on said wrapping material, a folding way above said another station, wrapper tucking blades adjacent three sides of said folding way to tuck three flaps of the wrapper under the boat and product, lever means for reciprocating said tucker blades, said lever means being interposed between a reciprocating actuating element and said tucker blades and having a pivot intermediate its ends and adjustable longitudinally of said lever means, a threaded shaft coating with said pivot to effect such adjustment, means for pushing the partially wrapped packages from said folding way and thereby folding the remaining flaps thereof, and a take-away conveyor receiving finished packages from said folding way.

17. A wrapping machine comprising card feeding and cutting, and boat forming mechanism, an arbor adapted to hold a roll of cardboard from which the cardboard may be withdrawn, means to frictionally restrain said arbor against rotation, means for withdrawing cardboard from the roll of cardboard and scoring the same, said scoring means comprising a pair of scoring rolls and means for adjusting the distance apart thereof comprising a shaft having oppositely pitched threads, one coating with one of said scoring rolls and the other coating with the other one to simultaneously adjust them toward or away from each other, cutoff means for the cardboard to cut it into cards, forming means for the cards to form them into channel-shaped boats comprising plows for bending up side flanges beyond the score lines of the card, hold-down flanges engaging with tops of the cards adjacent the scored lines and cooperating with said plows in forming the flanges of the boat, means for adjusting the width between said flanges comprising a shaft having oppositely pitched threads, one coating with each of said flanges to simultaneously adjust them toward or away from each other, means for rapidly projecting the boat after it is formed away from said boat forming mechanism, a card transfer conveyor for receiving the boat from said projecting means, said transfer conveyor having spaced projections for stopping the projected boats and for spacing them on the conveyor, said transfer conveyor carrying the boats past a pair of feed stations on opposite sides of said transfer conveyor at which alternate boats may be fed with product, said transfer conveyor delivering the boats with product thereon to a designated station on said transfer conveyor, a pusher for pushing the boat and product from said designated station to another station, means for feeding wrappers to a position over said another station, a folding way above said another station, said folding way being adjustable as to width and length, wrapper tucking blades adjacent three sides of said folding way to tuck three flaps of the wrapper under the card and product, said tucker blades being readily replaceable with others of different width, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, heat-sealing mechanism for the packages and operable to heat-seal the flaps thereof, and hold-down belts for the packages located above said take-away conveyor, said hold-down belts being adjustable toward and away from each other for different widths of product, the means for effecting such adjustment comprising a pair of adjusting shafts having opposite pitched

for feeding a strip of wrapping material, cutting the same into wrappers and delivering the wrappers to a position over said another station, said wrapper feeding mechanism being adjustable to accommodate different widths of wrapping material and having electric eye means controlling said cutting mechanism, said electric eye means including light beam mechanism cooperating with patterns on the wrapper material, said light beam mechanism having a unit which is adjustable to either face of the wrapper for transmitted light when on the opposite side of the wrapper from the light source, and for reflected light when adjusted to the same side thereof, a folding way above said another station, means for elevating a boat, product and a wrapper through said folding way, tucking the flaps thereof and pushing the package from said folding way, a take-away conveyor receiving finished packages from said folding way, and heat-sealing means for the flaps of the package.

18. In a wrapping machine, card feeding and cutting, 20 and boat forming mechanism comprising an arbor adapted to hold a roll of cardboard from which the cardboard may be withdrawn whereupon the roll will rotate said arbor, means to frictionally restrain said arbor against rotation, means for withdrawing cardboard from the roll of cardboard and scoring the same, said scoring means comprising a pair of scoring rolls and means for adjusting the distance apart thereof comprising a shaft having oppositely pitched threads, one coating with one of said scoring rolls and the other coating with the other one to simultaneously adjust them toward or away from each other, cutoff means for the cardboard to cut it into cards, forming means for the cards to form them into channel-shaped boats comprising plows for bending up side flanges beyond the score lines of the card, hold-down flanges engaging the tops of the cards adjacent the scored lines and cooperating with said plows in forming the flanges of the boat, means for adjusting the width between said flanges comprising a shaft having oppositely pitched threads, one coating with each of said flanges to simultaneously adjust them toward or away from each other, 30 means for rapidly projecting the boat after it is formed away from said boat forming mechanism, a card transfer conveyor for receiving the boat from said projecting means, said transfer conveyor having spaced projections for stopping the projected boats and for spacing them on the conveyor, said transfer conveyor carrying the boats past a pair of feed stations on opposite sides of said transfer conveyor at which alternate boats may be fed with product, said transfer conveyor delivering the boats with product thereon to a designated station on said transfer conveyor, a pusher for pushing the boat and product from said designated station to another station, means for feeding wrappers to a position over said another station, a folding way above said another station, said folding way being adjustable as to width and length, wrapper tucking blades adjacent three sides of said folding way to tuck three flaps of the wrapper under the card and product, 40 said tucker blades being readily replaceable with others of different width, lever means for reciprocating said tucker blades, said lever means being of adjustable length to vary the strokes of said blades, means for pushing the partially wrapped package from said folding way and thereby folding the remaining flap of the package, a take-away conveyor adapted to receive the wrapped package from said folding way, heat-sealing mechanism for the packages and operable to heat-seal the flaps thereof, and hold-down belts for the packages located above said take-away conveyor, said hold-down belts being adjustable toward and away from each other for different widths of product, the means for effecting such adjustment comprising a pair of adjusting shafts having opposite pitched
